UNDERGARMENT

Merle Speicher, St. Louis, Mo.

Application February 7, 1947, Serial No. 726,997

4 Claims. (Cl. 66—177)

1

This invention relates to undergarments and more particularly to elastic undergarments of the form-reducing or form-shaping type.

A main object of the invention is to provide a novel and improved elastic undergarment which is very simple in structure, very durable and very comfortable to wear.

A further object of the invention is to provide an improved elastic undergarment of the knitted type which is substantially seamless and wherein the garment is constructed to yield in a substantially uniform manner at points of increased bulk without overstressing the threads of elastic yarn at said points and which is adapted to conform smoothly to the natural contours of the wearer's body without imposing excessive restraint on the wearer, and whereby natural body movements are substantially uninhibited.

Further objects and advantages of the invention will become apparent from the following description and claims, and from the accompanying drawings which illustrate by way of example one form of the invention, and wherein:

Figure 1 is a front elevational view of a pair of woman's elastic under pants constructed in accordance with the present invention.

Figure 2 is a side elevational view of the garment shown in Figure 1.

Figure 3 is an enlarged detail view of a portion of the knitted structure employed in the garment of Figure 1, said detail view showing the manner of expanding the number of thread loops of the garment at certain specified critical points in order to provide additional garment area at said points.

Referring to the drawings, 11 designates an undergarment comprising a pair of woman's under pants. The undergarment is knitted in horizontal stitch courses and the yarn employed is of an elastic type, such as nylon-wrapped rubber, or a similar yarn having elastic qualities. The garment is seamless throughout and includes a crotch portion 12 of non-elastic yarn. The waist is knit to form a hem at 13 and similar hems are knit at the edges of the leg portions, as shown at 14, 14.

By making the garment seamless throughout the possibility of stitches unravelling and causing "runs" such as are common in hose and other garments is substantially reduced, as compared with garments having cut inserts, inasmuch as cutting a knitted fabric tends to encourage unravelling of the yarn.

In order to provide additional garment area in accordance with widened female anatomy con-

2

tour at the hips, the knitted stitch courses are gradually expanded downwardly at four substantially equally spaced regions beginning at points in the upper intermediate portion of the garment. The points where expansion of the stitch courses begins in the front portion of the garment are substantially symmetrically located and are shown in Figure 1 at 15, 15. The rear side of the garment has similar symmetrically located points 16. The stitch courses are contracted downwardly from the intermediate portion of the garment to inner points on the leg portions thereof, as shown at 17, 17 in Figure 1. The rear sides of said leg portions also have contracting stitch courses identical with and symmetrical with those of the front sides with respect to the plane of the garment.

Figure 3 illustrates the method employed to produce the expanded or contracted stitch courses. The loops 18, 19 and 20 form part of a normal stitch course. The next adjacent course has three loops 21, 22 and 23 passing through the loop 19 instead of one loop as in a normal stitch course. This increases the number of loops in said adjacent course by two additional loops, as compared with a normal stitch course. The next succeeding stitch course may have multiple loops passing through each of the loops 21, 22 and 23, or only through loop 22, depending upon the degree of stitch loop expansion required. In either event, the area of material increases laterally with each succeeding expanded stitch course. The contracted stitch courses are formed by reversing the above procedure. Considering Figure 3, loops 21, 22 and 23 would then be regarded as lying in a normal stitch course and the loop ends 24, 25, 26 and 27 would engage a single loop 19 in the contracted stitch course.

By expanding the stitch course downwardly from points 15 and 16 and upwardly from the leg points 17 maximum garment area is obtained at the hip portions of the garment so that the garment will fit comfortably and will not be excessively stretched or tensioned at any point thereof. The above described method of knitting also eliminates the necessity of providing inserts of material at the intermediate portion of the garment to provide the required increased garment area. As a result the garment is substantially seamless and its durability is greatly increased since the tension on the loops is substantially uniform over the entire area of the garment when it is being worn.

While the embodiment specifically illustrated herein is directed to under pants, the principle

of the invention is also applicable to other elastic or semi-elastic garments such as girdles, corsets, brassières, and the like, and all such further applications as may occur to those skilled in the art are contemplated within the spirit of the invention. Therefore, it is intended that no limitations be placed on the invention except as defined by the scope of the appended claims.

What I claim is:

1. An elastic form fitting substantially seamless undergarment made of continuously knitted elastic yarn arranged in successive horizontal stitch courses, the courses being increased downwardly as to number of stitch loops therein at four substantially equally spaced points around the intermediate portion of the garment and being increased upwardly in stitch loops from certain symmetrically located points in the lower portion of the garment. 10
2. An elastic form fitting substantially seamless undergarment made of continuously knitted elastic yarn arranged in successive horizontal stitch courses, the courses being gradually increased downwardly as to number of stitch loops therein from four substantially equally spaced points around the upper portion of the garment and being gradually increased upwardly in stitch loops from at least two symmetrically located points in the lower portion of the garment. 20
3. An elastic form fitting substantially seamless pair of under pants made of continuously knitted elastic yarn arranged in successive horizontal stitch courses, the courses being gradually increased downwardly as to number of stitch loops therein from two symmetrically located front points and from two symmetrically located rear points in the upper portion of the pants, the points being substantially equally spaced around 30
- 35

the pants, the courses in the leg portions of the pants being gradually increased upwardly as to number of stitch loops therein from at least two points in said leg portions symmetrically located with respect to the crotch of said pants.

5. An elastic form fitting substantially seamless pair of under pants made of continuously knitted elastic yarn arranged in successive horizontal stitch courses, the courses being gradually increased downwardly as to number of stitch loops therein from two symmetrically located front points and from two symmetrically located rear points in the upper portion of the pants, the points being substantially equally spaced around the pants, the courses in the leg portions of the pants being gradually increased upwardly as to number of stitch loops therein from a pair of inner points on each leg portion, the pairs being symmetrically located with respect to the crotch of the pants. 15
